UNITED STATES PATENT OFFICE.

JEHYLEMAN SHAW, OF BRIDGEPORT, CONNECTICUT.

DRIVEN WELL.

SPECIFICATION forming part of Letters Patent No. 278,751, dated June 5, 1883.
Application filed August 1, 1882. (No model.)

To all whom it may concern:

Be it known that I, JEHYLEMAN SHAW, of Bridgeport, in the county of Fairfield and State of Connecticut, have invented a new and useful Improvement in Driven Wells, of which the following is a full, clear, and exact description.

It is now the practice in sinking driven wells, where the water-bearing stratum is more than twenty feet below the surface, to excavate the earth down to within that distance of the water-bearing stratum and then to drive the pipe from the bottom of this excavation.

The object of my invention is to avoid the necessity of excavating. In some cases I make use of a large pipe to be driven the whole distance to the water-bearing stratum, while in others I use both a large and small pipe suitably coupled together, and I make use of a pump-valve or plunger that is adapted to work both upon the suction and lift principles.

Reference is to be had to the accompanying drawings, forming part of this specification, in which similar letters of reference indicate corresponding parts in all the figures.

Figure 1 is a sectional elevation of the lower portion of the large pipe or tube, having the valve located near the bottom thereof. Fig. 2 is a front elevation, showing the large and small pipe and coupling; and Fig. 3 is a central longitudinal elevation of the large tube and double-acting plunger.

In all cases where the soil is difficult to penetrate I prefer to drive the large pipe A the whole depth of the well. This pipe is about two inches or two and one-half inches in diameter, and is made in sections and provided at its lower end with the perforated point B, and is adapted to be driven into the ground section after section, in the ordinary way; but in case the soil is light I shall use the large pipe A' and the small inch and one-quarter pipe C, which pipes, in the process of driving, will be coupled together at the proper time by the conical coupling D. The pipe C will not in any case be more than twenty or twenty-six feet in length. It will be made in sections, and its lower section will be provided with the perforated point B', and in sinking the well this pipe C will be driven into the ground first, in the ordinary manner. The pipe A' will also

be in sections, and when the pipe C (twenty-six feet or less in length) has been driven into the earth the coupling D will then be screwed or otherwise secured upon the upper end of the last section thereof, and a section of the large pipe A' will then be screwed or otherwise secured to the coupling. The driving will now be continued, section after section of the pipe A' being added, until the point B' shall have been projected into the water-bearing stratum. In case the large pipe A is used the whole depth of the well, the plunger or valve E will be located in the pipe near the upper end of the point B, as shown in Fig. 1, so that it will stand near the water or partly or wholly submerged in the water; or it may be located any suitable distance less than twenty-six feet above the water, as may be deemed best, according to the construction of the plunger used; but in case the small pipe C and the large pipe A' are combined in forming the well the valve or plunger will be located in the pipe A' immediately above the coupling between these two pipes. In the former case the valve or plunger, if located at the bottom of the tube, when operated must act upon the lift principle and lift the water in the tube, and any lifting-valve may be used. If located above the point B, the water must be raised first by suction and then lifted, so that in that instance a double-acting valve must be used; and a double-acting valve must also be used in case the small pipe C is used in forming the well, the water being drawn by suction through the pipe C and lifted in or through the pipe A' to the spout or discharge. The double-acting valve or plunger E, which I have invented for this purpose, is shown clearly in Fig. 3, and consists of the stationary shell 90 or casing e, reciprocating plunger g, plunger-rod h, (to which the plunger is attached,) water-tube j, sleeve g', attached to the plunger g, and the tight packing k. The tube j leads from the packing k to the top of the pump, and the water is elevated up through it, and the plunger-rod h leads up through it to the pump-curb, where it is connected with the pump-handle. The shell or casing e is screwed upon the lower end of the tube j, and is thereby held stationary; and this shell or casing is of smaller external diameter than the internal

diameter of the pipe A or A', so that the annular water-space l is formed around it, and it is provided at its lower end with the flap-valve m, and is perforated at its upper end, as shown

5 at i i, and these openings are closed from the inside of the casing by the rubber or leather collar b, which acts as a valve to all of the openings. The plunger g is provided with the sleeve g', which extends up into the tube j and reciprocates with the plunger, and is provided

10 at its lower end with the flap-valve a, and is formed with the series of holes i' i' at its upper end, which are closed from the inside of the plunger with the leather or rubber collar b', which acts as a valve to close these openings

15 upon each downward movement of the plunger. The packing k is of rubber or similar material, and is practically air-tight in the pipe A, and serves also to keep the tube j centered in

20 the pipe A or A'.

The action of the valve or plunger is as follows: Upon the downward movement of the plunger the holes i' i' will be closed by the collar b', and a vacuum will be formed in the space in the shell or casing e above the plunger, which will cause the water to be drawn from the annular space l into this space. At the same time the valve m will be closed, and in case the space in the shell or casing between

25 this valve and the plunger is full of water the water will pass up through the valve a into the interior of the plunger and tube g'. Now, upon the upward movement of the plunger the

30 valves b and a will be closed and the valves b' and m will be opened, so that the water in the shell e above the plunger will be forced through the openings i' i' into the interior of the plunger and tube g', and this water and the water

35 already therein will be elevated into the tube j. At the same time a vacuum will be formed in the space in the shell e below the plunger, causing the water to fill this space through the valve m, ready to be forced up into the interior

40 of the valve g upon its next downward movement, which movement will again fill the space above the plunger. In this manner it will be seen that the plunger is double-acting, receiving and discharging water both from above and below at each reciprocation.

45 50 The plunger-rod h and the tube j will in most cases be in sections and of about the same length as the sections of the pipe A A', and these parts may be put in at the time and as fast as the sections of the pipe are driven, the casing

g and packing k being placed in and secured 55 in one of the lower sections of the pipe A' before driving; but I prefer to complete the driving of the pipes A or A', and then lower the pipe j with the packing k and plunger, casing, and valve into them, thus avoiding all 60 danger of injuring these parts in driving, and when put down in this manner they may be easily taken up for repairs without disturbing the pipes of the well.

By this method of driving wells it will be 65 seen that water may be elevated any height, and that the difficulty now experienced in obtaining water from deep water-bearing stratum is entirely overcome.

Instead of making the casing e stationary in 70 the pipe A and adapting the plunger g to be reciprocated therein, this order might be reversed and not depart from the spirit of my invention; and instead of using the separate small tube j and the large pipe A', extending the whole distance from the coupling D to the surface, a section or two sections only of the large pipe A' could be used, the remainder being pipe 75 C the same size as the pipe C, coupled to the upper end of the large pipe. In such construction the sections of large pipe would constitute 80 a chamber for the plunger, and the sleeve g' would extend from the plunger up into the small pipe, the plunger-rod being operated within the upper small pipe, the same as in 85 the pipe j.

When the pipe C is used it will be understood that the well will be much cheaper than when the well is formed entirely of the large pipe A, since the pipe C can be driven more easily and rapidly, and is of itself less expensive, than 90 the large pipe.

Having thus described my invention, what I claim as new, and desire to secure by Letters Patent, is—

1. In a driven well, the combination, with 95 the small pipe C, of the large pipe A', coupled thereto by the conical coupling D, substantially as and for the purposes set forth.

2. The pipe A', provided with a double-acting 100 plunger, in combination with the small pipe C and the coupling D, substantially as described.

JEHYLEMAN SHAW.
